The Lowell Manufacturing Company.

The exclusive right to use the lettered Patent, and make part of the same.

To all whom it may concern:

It is known that I, Clemir J. Ney, of Lowell, in the County of Middlesex and State of Massachusetts, have originated and designed a new Pattern for Carpets or other fabrics, of which the following is a full, clear and exact description, reference being had to the accompanying drawings, making part of this specification.

The principal features of this design are two series of figures, each consisting of a cross and four balls,

Alternating with the above mentioned series are two other series of figures, each consisting of a solid block surrounded by a three set figures.

The remainder of the design consists of small groups of set figures, each containing a diamond block, cross and cross.

The colors employed for the different portions of the design may be varied to suit the taste and whim of the manufacturer.
